US00D615063S

(12) **United States Design Patent**
Jeong et al.

(10) **Patent No.:** **US D615,063 S**
(45) **Date of Patent:** **** May 4, 2010**

(54) **MOBILE PHONE**

(75) Inventors: **Jong-Il Jeong**, Seoul (KR); **Nam-Mi Kim**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/340,916**

(22) Filed: **Jul. 28, 2009**

(30) **Foreign Application Priority Data**

Mar. 25, 2009 (KR) 30-2009-0012543

(51) **LOC (9) Cl.** **14-03**

(52) **U.S. Cl.** **D14/138 AB**

(58) **Field of Classification Search** ..... D14/138 AB, D14/138 R, 138 AD, 345, 346, 147, 203.4, D14/203.7, 203.2, 144; 455/575.3; 379/433.1, 379/433.11, 433.13; D21/517
